UNITED STATES PATENT OFFICE.

BYRON C. ROSS AND JOSEPH E. ZOMMIR, OF SPRINGFIELD, MASSACHUSETTS, AS
SIGNORS TO THE DIAMOND MATCH COMPANY, OF CHICAGO, ILLINOIS, A CORPORA-
TION OF ILLINOIS.

COMPOSITION-APPLYING MECHANISM FOR MATCH MACHINES.

Application filed October 6, 1925. Serial No. 60,806.

This invention relates to composition-applying mechanism for match making machines; having reference more especially to continuous machines for making paper or cardboard strips of matches which are subsequently subdivided into match cards of proper size for use in the manufacture of so-called "book matches". Machines of this type include an endless carrier by means of which cards of staggered match splints are transported through a match making cycle, including a vat containing ignitable composition, which composition is carried in a thin layer into the path of the free ends of the traveling splints by means of a transfer roll that is partially immersed in the contents of the vat. The free ends of the splints, with their broad faces disposed transversely of the path of travel, are moved tangentially of the roll and through the peripheral layer of composition on the latter. Such faces are therefore well supplied with composition, but the thin edges of the splints, being parallel with the direction of travel, are sparsely covered with the composition, thus resulting in the formation of imperfect match heads.

The object of our invention is to overcome the defective operation above mentioned, and to that end we provide simple and efficient mechanism whereby the free ends of the splints are uniformly dipped in a layer of match composition during the travel of the carrier, as will be hereinafter described and claimed.

In the drawings—

Figure 1 is a side elevation of a portion of a match making machine equipped with composition applying mechanism embodying our invention.

Fig. 2 is a side elevation, enlarged, of the composition applying mechanism.

Fig. 3 is a plan of the same.

Fig. 4 is a longitudinal vertical section of the composition tank and its appurtenances, showing a portion of the match carrier as supplied with cards of splints and matches.

Fig. 5 is a plan of the tank and the composition carrying apron therein.

Fig. 6 is a transverse vertical section 50 through the tank, as on the line 6—6 of Fig. 4.

Referring to the drawings, 10 designates a portion of the traveling endless carrier of a

match making machine, which carrier comprises a chain of links constructed to receive 55 succeeding cards C of match splints and carry them in spaced relation to each other through the match making path.

Removably supported beneath the carrier and the depending cards of splints by means of a suitable platform 11, is a tank 12 which is adapted to contain match head composition in a liquid state. The composition is conveniently supplied to the tank from an overhanging reservoir 13, the uniform level of 65 the composition within the tank being maintained by usual devices.

Mounted upon suitably-disposed rollers 14, 15 within the tank is an endless apron 16, of rubber composition or other appropriate 70 flexible material, the upper horizontal run of which apron is adapted to travel longitudinally of the tank and on or about the level of the contained composition. The width of the apron is somewhat greater than the 75 length of a card of match splints, and the longitudinal edges of the apron are provided with upstanding beads or flanges 17 between which is afforded on the upper horizontal run of the apron a shallow channel the depth 80 of which is substantially that of a match head. Hence during the travel of the apron a thin layer of composition of suitable depth 85 for the formation of match heads is carried continuously along the upper run of the apron.

The rollers 14, 15 are mounted on transverse shafts 18, 19 located near the respective ends of the tank. The roller 14 is fast on the shaft 18 and the latter is journaled in 90 bearings 20 at the sides of the tank, one end of the shaft extending outward and being operatively connected with a suitable source of power. In the present instance the shaft 18 is provided with a gear 21 in mesh with a gear 22 on a shaft 23 which is connected with and driven from a shaft of the match machine. Thus the roller 14 is continuously rotated and the apron 16 is impelled at the proper speed and in the proper direction, i. e., the upper run of the apron, with the layer of composition thereon, moves at the same speed and in the same direction as the adjacent portion of the match card carrier.

The roller 15 is loose on the shaft 19, and the latter has its bearings in a pair of arms

24 that are pivoted, as at 25, to the respective side walls of the tank so as to permit the roller 15 and the proximate portion of the flexible apron to be swung upward and above the tank (when the tank is pulled outward) as occasion may require, as indicated by dotted lines in Fig. 2.

Preferably suitably-disposed brackets 26, 27 on the inner sides of the tank serve as 10 stops to support the arms in their respective horizontal and raised positions.

Any suitable means may be used in connection with the tank 12 for heating the contained composition and keeping it in a liquid 15 condition. In the present instance this is conveniently accomplished by arranging the usual steam-jacketed composition vat 28 in inverted position beneath one end of the tank, as seen in Figs. 1 and 2.

20 The match card carrier in a part of its travel is supported and guided above the tank by sectional rails borne by a vertically movable frame structure, which structure includes two pairs of parallel bars 29 that 25 extend longitudinally of the carrier and are jointed at their outer ends to suitable supports, as at 30, 31. The inner or meeting ends of these bars are jointed by a cross-shaft 32 equipped with antifriction rolls 33, which 30 rest upon a pair of sector cams 34. These cams, which are mounted on studs 35 projecting from brackets on a pair of standards 36, are simultaneously operable by suitable 35 crank and link connections 37 to lift or to permit the descent of the flexibly connected ends of the frame bars, thus correspondingly moving the sectional guide rails, the part of the carrier thereon and its depending cards of splints.

40 The carrier is raised and lowered, as just described, preparatory to the stopping and starting respectively of the machine, the mechanism for this purpose being of known construction. Heretofore the carrier when 45 in down position moved in a fixed path across the composition applying roll, so as to advance the depending ends of the splints through the layer of composition on the periphery of the roll. According to our 50 invention, however, the carrier when down travels in a path which effects the dipping of the splints into the layer of composition on the upper run of the apron, and thereafter gradually raises the splints above the composition and permits them to pass clear beyond the tank, the ascending portion of the carrier being vertically vibrated in a manner to dip the splints into and lift them from the 55 layer of composition, similar to manual dipping; thus insuring the formation of uniform "heads" on the splints.

The rails which support and guide the carrier above the tank comprise at each side of the tank, three succeeding sections 38, 39, 40.

60 65 The section 38 is supported by brackets 41,

42 depending from the adjacent frame bar 29, the outer end of such section resting loosely on the bracket 41 and the inner end of the section being pivoted, as at 43, to the bracket 42. This section 38 is provided adjacent the receiving end of the tank with a decline 44 merging with a lower horizontal portion 45 of substantial length, and hence the portion of the carrier traveling on the section 38 is lowered and horizontally guided in a manner to dip the splints into, and advance them for a prolonged interval through the layer of composition on the apron. The second section 39 is pivoted at one end, as at 46, to the bracket 42 and thence 70 normally inclines upwardly to the foot of a link 47 to which it is pivoted at the other end, as at 48, so as gradually to raise the portion of the carrier imposed thereon and thus 75 lift the progressing splints above the tank. 80 The third section 40 is pivoted at one end, as at 49, to the foot of the link 47 and extends horizontally in the normal plane of the rail to a depending frame bracket 50, to which 85 such section is pivoted, as at 51.

The links 47 to which the sections 39, 40 at the respective sides of the machine are jointed are connected by means of straps to eccentrics 52 fast on an upper transverse shaft 53 having its bearings in standards 54 supported by the movable frame structure, and hence when the shaft 53 is actuated the two pairs of rail sections 39, 40, together with the portion of the carrier borne thereby, are rapidly vibrated vertically, and in consequence the splints which depend from the series of carrier links supported on the inclined rail sections 39, are moved down into and up from the underlying layer of composition in a manner to effect the described 100 uniform dipping of the splints in the underlying layer of composition on the apron.

In the present instance the shaft 53 is equipped with a sprocket wheel 55 which is connected by means of a chain 56 with a 110 similar wheel 57 on a shaft 58 which is geared with and actuated by the driven shaft 23 previously referred to.

From the foregoing it will be seen that our 115 invention is characterized by the provision of an endless flexible element mounted to travel within and longitudinally of a composition-containing tank and having a continuous shallow channel which affords in the upper run of the apron an elongated receiver 120 and conveyer for a uniform horizontal layer of composition into which the free ends of the splints borne by the carrier are effectually dipped in a manner closely approximating the manual method of dipping matches; 125 thereby insuring the formation of uniform heads on the match splints as previously mentioned.

It is to be understood that our invention is 130 not limited to the particular construction

herein disclosed, as the mechanism may be modified within the principle of the invention and the scope of the appended claims.

We claim—

- 5 1. In a match making machine having an endless flexible carrier for the match splints, the combination with said carrier, of a composition-containing tank located below the path thereof, an endless flexible apron mounted to travel within and longitudinally of said tank and having a continuous shallow channel which affords in the upper run of the apron an elongated receiver and conveyer for a uniform horizontal layer of composition, means for impelling the said apron concurrently with the carrier, means for permitting the portion of the carrier over the tank to drop, to permit the ends of the splints to enter the composition on the 10 apron, and means for effecting a relative vertical movement between the upper run of the apron and the dropped portion of the carrier, whereby the depending splints in such portion are dipped in the layer of composition conveyed by the apron. 15
2. In a match making machine having an endless flexible carrier, the combination with said carrier, of a composition-containing tank located below the path thereof, an endless flexible apron mounted to travel within and longitudinally of said tank and having a continuous shallow channel which affords in the upper run of the apron an elongated receiver and conveyer for a uniform horizontal layer of composition, means for impelling the said apron concurrently with the carrier, rails having jointed sections upon which a portion of the carrier is supported directly above the upper run of the apron, and means for vibrating said rail sections toward and from the apron. 20
3. In a match making machine having an endless flexible carrier, the combination with said carrier, of a composition containing tank located below the path thereof, an end- 25
- 30
- 35
- 40
- 45
- less flexible apron mounted to travel within and longitudinally of said tank and having a continuous shallow channel which affords in the upper run of the apron an elongated receiver and conveyer for a uniform horizontal layer of composition, means for impelling the said apron concurrently with the carrier, rails for supporting and guiding said carrier directly above the apron, said rails including relatively stationary sections which depress the carrier toward the upper run of the apron and maintain it in depressed position for a prolonged interval, and including also vibratory inclined sections which gradually raise the progressing carrier, and means for vertically vibrating said inclined sections during the travel of the carrier. 50
4. In a match making machine the combination of an endless flexible carrier for match splints, a vertically movable frame structure, jointed rail sections thereon upon which the carrier is supported and guided, means for raising and lowering portions of the jointed rail sections to raise and lower 55 the portions of the carrier thereon, a composition-containing tank located below the path of the portion of the carrier supported by the rail sections, an endless flexible apron mounted to travel within and longitudinally 60 of said tank and having a continuous shallow channel which affords in the upper run of the apron an elongated receiver and conveyer for a uniform horizontal layer of composition, means for impelling the said apron concurrently with the carrier, and means mounted on said structure for vertically vibrating certain of said rail sections when the structure is in down position. 65
